UNITED STATES PATENT OFFICE.

FREDERICK ALEXANDER WARD AND WILLIAM NEWTON TAYLOR, OF TOLEDO, OHIO.

GEAR-GRINDING MACHINE.

1,104,589.

Specification of Letters Patent. Patented July 21, 1914.

Application filed October 15, 1909. Serial No. 522,802.

To all whom it may concern:

Be it known that we, FREDERICK A. WARD and WILLIAM N. TAYLOR, citizens of the United States, and residents of Toledo, in the county of Lucas and State of Ohio, have invented certain new and useful Improvements in Gear-Grinding Machines; and we do hereby declare the following to be a full, clear, and exact description of the invention, such as will enable others skilled in the art to which it appertains to make and use the same.

Our invention relates to grinding machines, of the class described in Letters Patent, No. 888,675, granted to us under date of May 26, 1908, upon application, Serial No. 364,855, filed March 27, 1907.

This invention has reference more particularly to gear trimming or grinding machines, including means for trimming or truing the grinding medium thereof after operating on the tooth of a gear, together with means for supporting and indexing the gear to be ground, and means for imparting proper relative movements to the grinding medium, the trimming or truing mechanism and the gear supporting means.

Considerable difficulty has been experienced in the manufacture of gears due to the warping thereof, which invariably occurs during the hardening or tempering process. This warping, while it may be very slight, is very perceptible in a running thereof, causing what may be termed a noisy or rattling gear, which is most objectionable when present in the gearing of automobiles or other machines in which quietness and smoothness of running is desired. Attempts have been made to true the gear teeth after the tempering thereof by passing a grinding-medium across the same, but these so far as we are aware have all been impractical and unsuccessful due to the absence of means for trimming the grinding-medium to compensate for the wear occasioned by each grinding operation.

The object of our invention is to obviate the above difficulties and to make the mechanical truing of gears possible by the provision, in combination with a grinding-medium movable relative to the teeth of a gear which is mounted for a properly timed intermittent rotation, of highly efficient mechanism for automatically trimming the gear-coating surface of the grinding-medium to cause it to conform to the shape and size of

the teeth acted on, so that when the trimming or truing of the gear is completed the contour of each tooth conforms exactly to that of all the others.

A further object of our invention is the provision of simple and efficient means for imparting a predetermined movement to the grinding-medium relative to its plane of reciprocatory movement whereby to compensate for the wear or gradually diminishing size of the grinding-medium after each operation on the gear.

The operation, construction, and arrangement of the parts of the invention are fully described in the following specification, and illustrated in the accompanying drawings, in which,

Figure 1 is a side elevation of a machine embodying the features of our invention. Figs. 2 and 3 are partial transverse sections of the same taken, respectively, on the dotted lines $x\ x$ and $x'\ x'$ in Fig. 1, the former showing the rear trimmers elevated as they appear immediately after making a cut, and the latter showing both sets of trimmers in lowered or normal position. Fig. 4 is an elevation of the end of the machine carrying the work, with portions broken away. Fig. 5 is an enlarged partial elevation of the opposite side of said end portion to that shown in Fig. 1. Fig. 6 is a vertical section on the dotted line $w\ w$ in Fig. 1. Fig. 7 is a top detail of a portion of the parts shown in Fig. 6. Fig. 8 is a sectional detail of a portion of the means employed to impart a vertical movement to the grinding-medium taken on the dotted line $y\ y$ in Fig. 9. Fig. 9 is an end elevation of the same with the grinding-medium removed, and Fig. 10 is a transverse section taken on the dotted line $v\ v$ in Fig. 2.

Referring to the drawings, 1 designates the frame, which is provided at one end with the elevated portion 1^a carrying the grinding parts and at the other end with the elevated portion 1^b , carrying the work mandrel and a portion of its controlling parts. The frame portion 1^a is formed on its top with a longitudinally extending slide-way 2 on which a carriage 3 is mounted for longitudinal movement relative to the frame to permit the grinding-wheel 4, which is revolvably carried at its inner end, to be moved forward and backward across the face of the gear-wheel 5, which latter is carried as hereinafter described. The grinding-wheel

4 is journaled in a bracket 6, which is slid-
ingly carried by a head 3^a, formed at the
inner end of the carriage 3, for vertical ad-
justment relative to the plane of movement
5 of the carriage. This adjustment is effected
at each return movement of the carriage by
the fractional revolution of a screw 7, which
is vertically mounted in the head 3^a and
passes through a threaded aperture in a boss
10 6^a formed on the inner side of the bracket 6,
as shown in Fig. 1. A ratchet-wheel 8 is
carried at the lower end of the screw-shaft
7 and is engaged by a pawl 9, which is piv-
oted to a ratchet-wheel incasing member 10,
15 as shown in Figs. 8 and 9. This incasing
member is loosely mounted on the screw-
shaft and has an arm 10^a projecting there-
from in position for a screw 11 thereon to
have contact with an alining portion of the
20 slide-way 2 just prior to the limit of return
or rearward movement of the carriage,
whereby to impart a predetermined degree
of revolution to the screw-shaft 7, the dotted
lines in Fig. 8 illustrating the action of said
25 parts. The arm 10^a is normally retained at
its limit of inward movement relative to the
carriage 3 by a coiled contraction spring 12,
secured as shown in Fig. 8, and this inward
movement is regulated by a contact screw
30 13 carried by the arm. It is apparent that
each lowering movement of the grinding-
wheel is very slight, being only sufficient
for the trimming made necessary by the
wear after a grinding operation, and that
35 such movement is regulated by the number
of threads per inch on the screw 7, the num-
ber of teeth on the ratchet-wheel 8, and the
throw given the pawl 9.

The grinding-wheel 4 is driven by a belt
40 14, which connects the sheave 15 on the
wheel shaft and the drive-sheave 16 car-
ried by a line or other suitably driven shaft.
The course of the belt is guided intermediate
the sheaves 15 and 16 by the two sheaves
45 17, 17, which are carried at the rear or outer
end of the carriage 3, as shown in Fig. 1.
The requisite longitudinal movement is im-
parted to the carriage 3 from the rotary
movement of a drum 18, which is mounted
50 on the shaft 19 beneath the carriage, due to
an idler-roll 20, carried at the under side of
the carriage, traveling in a cam groove 21
formed in the circumference of the drum,
said groove being shaped as hereinafter more
55 particularly described. A gear-wheel 22 is
carried at the outer end of the shaft 19, and
has connection through suitable interme-
diate gearing with a source of power.

Supported by the frame 1 intermediate
60 the elevated portions 1^a and 1^b thereof is the
frame part 23, which in turn supports the
standard or bracket 24. This standard or
bracket has its forward faces formed with
a horizontal groove 25 in each end of which
65 is slidingly mounted a block 26, which

blocks are yieldingly spaced apart by a
coiled compression spring 27 and are rela-
tively adjusted by adjusting-screws 28, as
best shown in Fig. 10. Secured to the for-
ward or outer face of each block 26 by a 70
bolt or stem passing through it and a hori-
zontal slot in the standard and receiving a
nut at the rear end, is a vertical socket 30,
which carries a vertically adjustable post
31. The lower end of each socket is closed
75 by a plug 32 through which an adjusting-
screw 33 is threaded, said screw coacting
with a spring-retainer 34, which is threaded
to the lower end of the post 31 and receives
the thrust of the lower end of a coiled com-
pression-spring 35. This spring encircles
80 the post and has its upper end thrust against
a shoulder in the socket, as shown in Fig. 2.
The post is locked in adjusted position by
a bolt 36, which passes through the retainer
34 and alining vertical slots in the socket
85 wall, as shown. The upper end of the posts
31 terminate in horizontally-disposed bearing-
heads 37, which are disposed adjacent
the lower arc of the grinding-wheel 4 on op-
90 posite sides thereof and in each of which is
mounted a rock-shaft 38. Radially project-
ing from the forward ends of the shafts 38
are the two opposing rear diamond-holders
95 39, each of which carries at one end a dia-
mond 40 for coacting with and trimming
the contiguous arc *a* of the grinding wheel
4. Each diamond-holder 39 passes through
a collar 41 carried by the shaft and is se-
cured in adjusted position by a set-screw 42.
100 These holders are intended to be so adjusted
relative to the grinding-wheel, when at its
limit of rearward movement, that the axis
of each coincides with the axis of the con-
tiguous arc *a* of the wheel, thus causing
105 them, when operated, to effect a superficial
trimming of the surfaces *a*, *a*, immediately
after each lowering movement of the wheel.
Projecting inwardly from the rear end of
each shaft 38 is an arm 43, which arms have
110 their inner ends lapping each other and
slotted, as shown, to receive a common pin
44^a carried at the upper end of the vertical
push-rod 44, so that a vertical reciprocatory
movement of the rod will impart a sim-
115 ultaneous rocking motion to the two shafts 38
and their diamond-holders 39. This rod
passes down through a hole in the standard
24 and frame part 23 and has its lower end
terminating in position to coact with the
120 conical face of a collar 45, which is slidingly
carried by a shaft 46, whereby as said collar
is moved from its normal position, by means
hereinafter described, the rod is raised
against the tension of the coiled compres-
125 sion spring 44^b to effect an upward movement of
the rear trimmer-diamonds 40 to trim the
arcs *a*, *a* of the grinding-wheel. The conical
collar 45 is returned to its normal position
130 by the action of the coiled compres-

spring 47, which is mounted on the shaft 46 intermediate said collar and the cam-faced collar 48, which is fixed to said shaft and has an additional function hereinafter described.

5 During the operation of the rear trimmer-diamonds 40 on the wheel 4 the idler-roll 20 of the carriage 3 is traveling in the neutral zone *a* of the cam groove 21 in the drum 18, and at the end of such zone enters the inclined or diagonally-disposed portion *b* of the groove, which causes the carriage to move forward until the axis of the grinding-wheel stands in vertical alinement with the two front trimmer-diamonds 49. At this 10 point the idler-roll 20 enters a second neutral zone *c* of the guiding-groove and effects a momentary pause of the carriage and grinding-wheel to permit said front trimmer-diamonds to act on the wheel before the idler-roll enters the inclined or diagonally-disposed portions *d* of the guiding-groove, which moves the carriage 3 forward sufficiently for the wheel 4 to traverse across the face of the gear 5 for the purpose of truing the contiguous faces of two of its teeth. The 15 guiding-groove 21 at the end of the diagonal portion *d* thereof is formed with a return bend and continues around the drum forming a reverse diagonal course which meets the neutral zone *a* thereof, thus returning the grinding-wheel to again be trimmed.

Mounted for reciprocal vertical movement in the socket-member 50, secured to the top of the frame part 23 in advance of the standard 24, is a plunger or push-rod 51, the lower end of which is projected through the top of said frame part 23 in position to coact with the cam surface of the collar 48 on the shaft 46, whereby a raising thereof is effected when the collar is turned. The upper end of said plunger or rod is projected to adjacent the lower edge of the grinding-wheel 4 when standing thereover and is bifurcated to form the two arms 52, 53, each of which 20 carries one of the front trimmer-diamonds 49 at its free end in position for their points to abut each other when the free ends of the arms are forced together and to have contact with the periphery or bead of the grinding-wheel when the plunger is elevated. The plunger is prevented from turning in its socket by keys 58 which operate in registering grooves in the socket walls. A coiled compression spring 54 encircles the plunger 25 within an enlarged part of the socket, and has its upper end abutting against a shoulder in the socket and its lower end coacting with a collar 55 on the plunger, thus tending to normally maintain the plunger in lowered position, as shown in Fig. 3. The lowering movement of the plunger is shown as being limited by a shoulder 51^a thereon coacting with a cap 50^a, which is secured to the upper end of the socket 50 and through which the 30 plunger operates.

Mounted on the socket-member 50 is a collar or head 56 from the opposite sides of which project the two upwardly extending arms 57, 57, the terminals of which converge and each carries an idler-roll 58 in position 70 to engage the outer face of the contiguous arm 52 of the plunger. As the tendency of the arms 52 is to diverge or remain in open position so that the diamonds 49 would normally be separated, the coaction of the rolls 75 58 therewith is intended to produce a converging of the diamonds at a predetermined point in the movement of the plunger. For this purpose the arms are provided with the raised surfaces *e* with which the rolls 58 coact when the plunger is down and continues to coact until the plunger is raised sufficiently for the diamonds 49 to have contact with the periphery or bead *b* of the grinding-wheel, at which point the arms begin to 80 spread, due to the rolls passing to the abruptly reduced surfaces *f* of the arms, thus permitting the diamonds 49 to have a diverging movement transversely of the narrow face or bead *b* of the rapidly revolving 85 grinding-wheel whereby to trim the same.

The cam-collar 48, with which the lower end of the plunger or push rod 51 coacts, is provided with an abrupt projection 48^a by means of which the plunger is suddenly elevated when the shaft 46 is given a partial revolution. The means employed for rocking the shaft 46, as shown in Figs. 1, 6 and 7, consists of a pin 59, which projects from said shaft in position to be struck by a finger 60 at each revolution of the drum 18, said finger being adjustably secured to the inner end of the drum. The shaft 46 and collar 48 are automatically returned to their normal position after the finger 60 has released the pin 59, due to the action of the coiled contraction-spring 61, which has one end fixed to a pin projecting from said collar and its other end fixed to a convenient portion of the frame, as shown in Fig. 3. The 95 return or backward movement of the shaft is limited by a lug 62 on the collar 48 engaging a stop 63 secured to a contiguous frame portion. 100

The gear-wheel 5 to be trued is carried 105 at the inner end of the horizontal arbor-shaft or mandrel 64, which is journaled in the elevated portion 1^b of the frame and carries the index-wheel or disk 65 at its outer end. The mechanism shown in Figs. 110 1, 4, 5, 6 and 7 by means of which the index wheel is moved with mechanical precision through any required portion of a revolution and locked in any adjusted position consists in loosely mounting a ratchet 115 wheel 66 on the mandrel 64 within a housing or casing 67 on the inner face of the index-wheel 65. This ratchet-wheel has an arm 68 radially projecting therefrom through a suitable opening in the casing 67 120 125 130.

and when moved by a raising of said arm has its teeth engaged by a spring-pressed pawl 69 which is carried by the housing 66 of the index-wheel so that movement is communicated thereby to the latter. An adjustable rod 70 connects the arm 68 with an arm 71 projecting from the disk-like member 72, which is loosely mounted on the rock-shaft 73 without the frame 1. The arm 71 has its lowering movement limited by a radial lug 74 on the member 72 coacting with a stop-screw 75 carried by the adjoining frame part. The shaft 73 is transversely journaled in the frame 1 beneath the arbor-shaft 64 and has a disk 76 fixed to its inner end within the frame 1, as shown in Fig. 1, and an arm 77 fixed to its outer end in position to coact with a screw 78 carried by a lug 79 on the face of the member 72. When the shaft 73 is rocked, as hereinafter described, the arm 77, after first having a limited movement relative to the member 72, engages the screw 78 thereon to impart the requisite turning movement to said member 25 for the purpose of elevating the rod 70 to effect a movement of the index-wheel 65.

A rod or link 80 connects the disk 76 with the lower end of a lever 81, which is fulcrumed to an arm projecting from the frame 30 beneath the shaft 46 and has its upper end forked and positioned to engage the lugs 82, which project in opposite directions from the sleeve 83. This sleeve is slidably carried by the shaft 46 beneath the drum 18, 35 and carries an idler-roll 84 for traveling in the cam-groove 21 of the drum, whereby a rotation of the drum imparts a reciprocatory movement to the sleeve. The sleeve is slotted, as at 83^a to permit its forward end to 40 move past the pin 59 on its shaft. At a predetermined point in the forward movement of the sleeve the lugs 82 thereon engage the forked end of the lever 81, causing an oscillation thereof and a consequent partial rotation of the disk 76 and shaft 73. In order to prevent a turning of the sleeve 83 an arm 83^b projects from one side thereof and has its outer end forked to have a sliding movement on a fixed bar 83^c, which is mounted 45 in parallelism with the shaft 46, as shown in Figs. 6 and 7. As the disk 76 is rotated an idler-roll 85 thereon moves upon a cam-surface 86 formed on the upper side of the arm 87, and causes a depression of the arm, 50 which depression is maintained during the remainder of the stroke. The arm 87 is pivoted at its rear end to a boss 88, projecting inwardly from one side of the frame 1, and has its forward end forked and embracing 55 the grooved collar 89, which is carried at the lower end of the vertical rod 90. This rod is mounted for vertical movement within a holder 91 secured to the end of the frame 1 and is normally retained elevated 60 by the action of the spring 90^a so that its

upper end engages one of the peripheral notches 65^a in the index-wheel 65 whereby to serve as a stop therefor. The journal-box in which the arbor-shaft or mandrel 64 is mounted is vertically adjusted by a hand-screw 92 to accommodate the machine to the truing of different sized gears. To permit of this adjustment the vertical rods 70 and 90 of the index-wheel controlling mechanism are both made longitudinally adjustable, as 75 shown.

The sliding-sleeve 83 on the shaft 46, in addition to communicating motion from the drum 18 to the lever 81 of the work-controlling mechanism, also serves as a means for 80 actuating the movement of the conical collar 45 carried on the shaft 46 therewith, as it engages the end of said collar just prior to its (the sleeve's) limit of forward movement, or approximately at the time the 85 idler-roll 20 of the carriage 3 enters the neutral zone *a* of the cam-groove 21 thus effecting a forward movement of the collar 45 against the tension of the spring 47 and a properly timed raising of the push-rod 90 44 to operate the rear trimmer-diamonds 40.

In Figs. 1, 2 and 3 is illustrated a suitable mechanism for manually controlling the trimming movements of the two sets of diamonds. This mechanism comprises a shaft 93, which is journaled in the frame part 23 in parallelism with the shaft 46, as shown in said figures, and carries an arm 94 for engaging the under side of a pin 95 projecting from the push-rod 44, and an arm 96 100 for having like engagement with a pin 97 projecting from the plunger or push-rod 51. The shaft 93 is mounted to have a limited longitudinal movement in its bearings and the arms 94 and 95 are relatively 105 positioned thereon so that when the shaft is at the limit of inward movement the former only is in position to engage its pin, and when at its limit of outward movement the latter only is in position to engage its pin. 110 An operating handle 98 is carried at the outer end of the shaft. It is thus apparent that when the shaft is pushed in and rocked in the proper direction an elevation of the push-rod 44 will be effected and when pulled 115 out and similarly rocked an elevation of the plunger or push-rod 51 will be effected.

The operation of the machine is as follows: The work being positioned on the arbor-shaft or mandrel 64, which is properly adjusted to suit the size of the same, the means driving the gear-wheel 22 is thrown into operation to impart the proper rotation to the drum 18, which in turn communicates a properly timed longitudinal 125 reciprocatory movement to the carriage 3 due to the idler-roll 20 carried thereby traveling in the circumferential cam-groove 21 of the drum. The forward movement of the carriage causes the rapidly revolving 130

grinding-wheel 4, carried thereby, to traverse the upper face of the work between two of the teeth thereof, thus truing or removing all uneven surfaces or irregularities on the sides of the teeth with which it coacts, it being understood, of course, that the rim of the grinding-wheel is shaped to conform exactly to the desired shape of such space. When the grinding-wheel has traversed the face of the work the movement of the carriage is reversed and the wheel thereby returned through the same groove or space of the work to its original point of starting. As the carriage nears its limit of rearward movement the screw 11 carried by the arm 10^a has contact with an alining stationary portion of the frame 1^a, thus effecting an oscillation of said arm and causing the dog or pawl 9 carried thereby to engage and impart a fraction of a revolution to the ratchet-wheel 8 and screw 7 to which said wheel is fixed and effecting a very slight lowering of the grinding-wheel. The lowering mechanism is so regulated and adjusted that the movement imparted to the grinding-wheel is only sufficient to allow for the necessary trimming of the wheel in order to true it after a grinding operation. The grinding-wheel having been lowered, the idler-roll 20 enters the neutral zone *a* of the cam-groove 21, thus causing a slight pause of the carriage 3 before again starting on its forward movement. During such pause the sliding-sleeve 33 on the shaft 46 strikes the extended end of the conical collar 45, moving it forward against the tension of the compression-spring 47 and effecting an elevation of the push-rod 44 due to the coaction of its lower end with the conical surface of the collar. This raising of the rod imparts simultaneous rocking movements to the two rear-trimmer diamond-holders 39, through the medium of the shafts 38 and arms 43, and causes the rear trimmer-diamonds 40 to move upward in unison in arcs concentric to the arcs *a*, *a* of the grinding-wheel whereby to trim such surfaces preparatory to said wheel truing the succeeding groove or space in the gear-wheel being operated on to that trued in the previous operation. After the push-rod 44 has been elevated the idler-roll 20 enters the diagonally-disposed portion *b* of the guiding-groove 21 which causes the carriage to move forward a sufficient distance for the axis of the grinding-wheel to stand in vertical alinement with the front trimmer-diamonds 49 of the trimming mechanism. At this point the idler-roll 20 enters the second neutral zone *c* of the groove 21, causing the carriage to again pause in its movement, during which pause the finger 60, carried by the drum 18, coacts with the pin 59 carried by the shaft 46. As the finger strikes the pin the shaft 46 and collar 48 thereon are

rocked sufficiently to throw the cam projection 48^a on said collar under the lower end of the plunger or push-rod 51, whereby to raise said plunger in position for the trimmer-diamonds 49 carried at its upper end to coact with the periphery or bead *b* of the grinding-wheel.

At approximately the point of contact of the diamonds 49 with the grinding-wheel the idler-rolls 58 pass abruptly from the raised surfaces *e* to the reduced surfaces *f* of the arms 52 of the plunger, thus permitting the diamonds 49 to have a diverging movement transversely of the narrow face or bead *b* of the rapidly revolving grinding-wheel, whereby to effect a smooth and even trimming of such surface. Upon a release of the two push-rods 44 and 51 they are, respectively, actuated by the springs 44^b and 54 to return to their normal lowered positions. A manual raising of the rods 44 and 51 may be effected by moving the shaft 93 in or out, respectively, and pressing down on the handle 98 so that the arms 94 will coact with the pin 95 on the rod 44 or the arm 96 will coact with the pin 97, as the case may be, and effect a raising of the respective rods. Near the limit of rearward movement of the carriage 3 the disk 76 receives a partial revolution, due to the sliding-sleeve 83 on the shaft 46 striking and oscillating the lever 81. As the disk is turned the idler-roll 85 carried thereby moves upon the raised cam-surface 86 of the pivoted arm 87, effecting a depression 100 thereof and a consequent disengagement of the member 90 from the registering notch in the index-wheel 65. The arm 71, which is keyed to the shaft with the disk 76 and turns therewith, is adjusted relative to the screw 75 carried by the member 72 so that it engages said screw immediately upon the release of the locking-member 90 from engagement with the index-wheel and effects a raising of the rod 70 and a consequent 105 partial rotation of the ratchet-wheel 66. As the ratchet-wheel is moved it engages the pawl 69 and imparts the requisite movement to the index-wheel and arbor-shaft or mandrel 64 to rotate the gear-wheel 5 the distance of one tooth, so that each groove of the gear-wheel is successively acted on by the grinding-wheel. Upon a release of the rod 90 it is elevated by the action of the spring 90^a.

While we have shown our trimming mechanism as associated with a particular style of gear-truing machine, we wish it understood that we do not limit ourselves to its use in such connection, nor do we wish to 125 restrict our invention to the particular construction or arrangement of the parts shown and described, as obvious modifications will occur to one skilled in the art.

Having thus described our invention, 130

what we claim as new and desire to secure by Letters Patent, is:—

1. In a machine for grinding gears or doing similar work, the combination of a grinding medium, for imparting a given contour to the work, means for supporting the gear to be operated upon, mechanism for imparting relative movement to the grinding medium and gear support to cause the grinding medium to engage the work, and means coöperating with the grinding medium to trim the operating surfaces thereof and maintain at said surfaces the contour to be applied to the gear.
  2. In a machine for grinding gears or doing similar work, the combination of a grinding medium, means for supporting the gear to be operated upon, mechanism for imparting relative movement to the grinding medium and gear support to bring the grinding medium and the gear teeth into coöperative engagement to effect a grinding of the teeth by and in accordance with the working face of said medium, and means coöperating with the grinding medium to trim the operating surfaces thereof and maintain at said surfaces the contour to be applied to the gear.
  3. In a machine for grinding gears or doing similar work, the combination of a grinding medium, supporting and indexing mechanism for the gear to be operated upon, mechanism for imparting relative movement to the grinding medium and gear support, and means coöperating with the grinding medium to trim the operating surface thereof to the contour to be imparted to the gear.
  4. In a machine for grinding gears or doing similar work, the combination of a grinding wheel having its peripheral portion shaped to conform to the surface to be ground, supporting and indexing mechanism for the gear, means for imparting relative movement to the grinding wheel and the gear support to cause the wheel to engage successive teeth of the gear, and mechanism coöperating with the grinding wheel to trim the peripheral portion thereof and maintain the same of the exact contour to be imparted to the gear.
  5. In a machine for grinding gears or doing similar work, the combination of a rotatable grinding medium, the operating surface of which conforms to the working face
- of the gear tooth, means for supporting the gear, mechanism for imparting relative movement to the grinding medium and gear support and for intermittently indexing the gear supporting means, and mechanism for trimming the grinding medium to maintain the same in exact conformity with the surface to be ground.
6. In a machine for grinding gears or doing similar work, the combination of a grinding medium having its working face of a contour complementary to the face of the gear teeth to be ground, means for supporting the gear to be operated upon, mechanism for bringing the working face of the grinding medium and the gear teeth into operative engagement, and a trimming mechanism coöperating with the grinding medium to restore the working face to its normal contour when said face becomes deformed.
7. The method of grinding gears or like articles to an exactly predetermined form, comprising the mounting of a rotary grinder in an organized work grinding machine, the trimming of the grinder wheel while thus mounted to fashion or re-fashion the cross sectional contour thereof to a predetermined form exactly complementary to the contour of each of a series of like segments in the cross section of the finished work, and in grinding the work by successively presenting segments thereof to the operation of the grinder.
8. The combination with an organized machine for grinding gears and the like, including a rotary work holder, an indexing mechanism therefor and a grinder having its axis transverse to the axis of the work, of means forming a part of the organized unit for trimming the grinder wheel to a predetermined cross sectional contour exactly complementary to each of a series of like segments in the contour of the finished work.
- In testimony whereof we affix our signatures in presence of two witnesses.
- FREDERICK ALEXANDER WARD.
WILLIAM NEWTON TAYLOR.
- Witnesses as to F. A. Ward:
GEO. P. CODD,
N. C. BANKS.
- Witnesses as to W. N. Taylor:
GEO. P. CODD,
BERTHA L. TAYLOR.
